GENERAL MOTORS CORPORATION, OF DETROIT, MICHIGAN, A CORPORATION OF
DELAWARE

RADIATOR

Application filed March 31, 1928. Serial No. 266,317.

This invention relates to radiator assemblies for automobiles. The conventional type of automobile is provided at its forward end with a radiator consisting of a core through which the engine cooling water is forced and with a shell concealing portion of the core and giving an ornamental appearance to the assembly. It is also customary to provide the radiator with shutters to control the flow of air through it and these shutters are frequently vertically arranged.

Our invention consists in an improved support for the radiator shutters which is much stronger than conventional designs and at the same time serves to give the appearance of a continuation of the radiator or of the radiator shutters, improving the appearance of the car. The support preferably takes the form of a panel secured to the bottom of the radiator shell and having portions exposed in the openings in the shell, the panel being formed with a supporting part or ledge receiving the bottom pivots of the shutters. Since the panel is removable it may be readily given any desired finish and configuration, preferably the same as the radiator shutters or the radiator core so that the appearance of a high radiator may be obtained.

In some cases it may be preferred to make the panel integral with the radiator shell and in this event the same effect may be obtained by painting or enamelling the lower portion of the shell also giving it a configuration resembling that of the radiator core or shutters.

35 In the drawings:

Figure 1 is a front elevation of the radiator assembly of a La Salle engine in which our invention is embodied.

Figure 2 is a section on line 2—2 of Figure 1.

Figure 3 is a section on line 3—3 of Figure 1 on a slightly larger scale.

Figure 4 is a rear elevation of the radiator shutter assembly including the finishing panel which supports the bottom pivots of the shutters.

Figure 5 is a side elevation of the same assembly.

Figure 6 is a section on line 6—6 of Figure 1.

Figure 7 is a front elevation of a portion of the structure shown in Figure 6.

Referring to Figure 1, 10 indicates the radiator shell, 12 the shutters provided with top pivots 14 and bottom pivots 16. The shutters are broken away to show a portion of the radiator core 18. 20 indicates a removable finishing panel having portions exposed at the lower end of the opening 22 provided in the shell. At 24 is shown the cover plate 30 for the usual aperture through which the starting crank may be inserted for rotating the crank shaft. The radiator shutters are mounted in a sub-assembly shown in Figure 4 and consisting of a top portion 26 and side portions 28 connecting the top portion with the panel 20. The top pivots of the shutters are journaled in flange 30 forming part of the top member 26 and the bottom pivots of the shutters are journaled in flange 32 formed on the upper edge of the panel 20. It will be noted that the panel 20 is provided with a peripheral strengthening flange 34 so that it is in effect a channel member offering considerable resistance to vertical loads such as that constituted by the weight of the shutters.

In the La Salle and Cadillac construction the radiator core 18 and the top and bottom tanks are secured to a chassis cross member, not shown, by means of studs 40 carrying suitable clamping devices 42. The radiator shell 10 is supported by the core in any suitable manner. The details of the supporting means for the core and for the shell form no part of this invention. However, member 44 indicates a supporting plate extending from part of the radiator core assembly and having a downturned flange 46 to which is bolted a similar flange 48 formed on stamping 50, best shown in Figure 5. The stamping 50 is provided with a horizontally extending flange 52 upon which rests the flange 32 formed on the upper end of the panel 20. The bottom pivots 16 of the radiator shutters pass through openings in the flange 32 and through openings 54 in a bar 56 carried by supports 58 welded to the flange 52.

Attention is called to the fact that the exposed portions of the panel 20 are ribbed to

resemble continuations of the radiator shutters 12. Where shutters are not employed the panel may be given a configuration to resemble the radiator itself. The panel is a separate fitting and may be readily finished in any desired color or with any desired material to match the finish of the shutters or of the core. Obviously the same effect may be obtained by making the panel an integral portion of the radiator shell and stamping it to the configuration desired and giving it the desired color.

It will be noted that the panel 20 constitutes a relatively stiff channel member and is consequently well adapted to take the load of the radiator shutters. A portion of this load is, however, transmitted directly to the radiator core assembly through the member 50 and the member 46.

It will be noted that the pivots of the radiator shutters are in close proximity to the core assembly or specifically to the top and bottom tanks of the core and consequently the heat radiated from the core will at all times prevent the pivots from becoming frozen. Were the shutters extended below the core freezing might occur and the shutters be rendered inoperative.

Obviously in the manufacture of the device the shutter assembly previously described is put together, the top member 26 is secured to the core assembly by suitable fastening means such as shown at 60, the flange 48 is secured to the flange 46 by fastening means 62 and the panel 20 is secured to the shell by fastening means 64. The last named connection is made only at the portion of the shell covered by the cover 24 so that the appearance of the assembly will not be marred by fastening bolts. The described construction is strong, makes it possible to give the radiator desirable lines and is well adapted for large production.

We claim:

1. A radiator assembly comprising a shell, a core in the shell, vertically arranged shutters mounted in front of the core, the shell being apertured, a removable finishing plate covering said aperture, said plate being provided with an inwardly extending flange serving as a support for the pivots of the shutters.

2. In the combination as defined in claim 1, said core extending to a point adjacent the pivots so as to prevent freezing thereof.

3. A radiator assembly comprising a shell, a core in the shell but spaced from the bottom thereof, vertically arranged shutters pivotally mounted in the shell and having their pivots in proximity to the core so as to prevent freezing thereof, said shell being provided with a removable panel below the shutters finished to resemble a continuation thereof.

4. In a built-in shutter device, the combination of a radiator core having attaching

devices secured thereto with a shutter frame carried by said devices, said shutter frame including a pair of bearing strips, and a plurality of shutters pivotally mounted in said bearing strips for controlling flow of air through the upper portion of said core, and said shutter frame having a false shutter apron for closing the lower portion of said core.

5. In a built-in shutter device, the combination of a radiator core having attaching devices secured thereto with a shutter frame carried by said devices, said shutter frame including a pair of bearing strips, a plurality of shutters pivotally mounted in said bearing strips for controlling flow of air through the upper portion of said core, and said shutter frame having a false shutter apron for closing the lower portion of said core, and a radiator shell engaged by said apron and by a spout on said core.

6. A radiator assembly comprising a shell, a core in the shell, vertically arranged shutters mounted in front of the core, the shell being apertured, a removable finishing plate covering the lower portion of said aperture, said plate being provided with an inwardly extending flange serving as a support for the pivots of the shutters.

7. A radiator assembly comprising a core, a shell surrounding the core and provided with an opening in its front face for exposing the core to a cooling air stream, vertically extending radiator shutters arranged in said opening and in front of the core, and a panel fitted in said opening and having its exposed face provided with vertical flutes in vertical alignment with the shutters.

8. A radiator assembly comprising a core, a shell surrounding the core and provided with an opening in its front face for exposing the core to a cooling air stream, vertically extending radiator shutters arranged in said opening and in front of the core, and a panel fitted in said opening below the shutters and having its exposed face provided with vertical flutes in vertical alignment with the shutters, said panel being provided with a transversely extending flange serving as a support for the pivots of the shutters.

9. In a built-in shutter device, the combination of a radiator core assembly having attaching means with a shutter frame carried by said means, said shutter frame including a pair of bearing strips, and a plurality of shutters pivotally mounted in said bearing strips for controlling flow of air through the upper portion of said core, and said shutter frame having a false shutter apron for covering the lower portion of said core assembly.

10. In a built-in shutter device, the combination of a radiator core assembly having attaching means with a shutter frame carried by said means, said shutter frame including a pair of bearing strips, a plurality

of shutters pivotally mounted in said bearing strips for controlling flow of air through the upper portion of said core, and said shutter frame having a false shutter apron for covering the lower portion of said core assembly, and a radiator shell engaged by said apron and by a spout on said core.

11. The combination of a radiator core, a shell for the core having the usual front opening exposing the core to a cooling air stream, said opening extending below the core, a shutter frame fitting in said opening and comprising top, bottom and side frame elements secured together, said bottom frame element being provided at its upper edge with a rearwardly projecting supporting ledge and a plurality of vertically arranged shutters pivotally supported by said ledge and said top member, said bottom frame element filling in the portion of the opening in the shell below the core and extending from one side of the shell to the other and being provided with vertical stiffening ribs, said bottom element forming a truss for taking the load of the shutters, and means for supporting said frame over the opening in the shell.

In testimony whereof we affix our signatures.

ERNEST W. SEAHOLM.
